CLAIM

The ornamental design for a smart battery module for an unmanned aerial vehicle, as shown and described.

DESCRIPTION

FIG. 1 is a top-front-left side perspective view of a smart battery module for an unmanned aerial vehicle of my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings are for the purpose of illustrating portions of the smart battery module for an unmanned aerial vehicle which form no part of the claimed design.
